BOX FOR MATCHES

Guglielmo Frascolla, New York, N. Y.

Application March 15, 1956, Serial No. 40,621

Term of patent 14 years

(Cl. D58—11)

FIG. 2.

FIG. 3.

FIG. 4.

FIG. 1.

Fig. 1 is a perspective view of a box for matches showing the cover portion removed therefrom and showing my new design;

Fig. 2 is a top plan view thereof in closed position;

Fig. 3 is an elevational view thereof; and

Fig. 4 is a bottom plan view thereof.

I claim:

The ornamental design for a box for matches, substantially as shown.
